JEWELRY DISPLAY SUPPORT

Edward E. Heberlein, Fennimore, Wis.

Application February 15, 1956, Serial No. 40,177

Term of patent 14 years

(Cl. D80—9)

Fig. 2.

Fig. 1.

Fig. 3.

Fig. 4.

Fig. 5.

Fig. 6.

Figure 1 is a perspective view of a jewelry display support embodying my new design and;

I claim:

The ornamental design for a jewelry display support, as shown.
